UNITED STATES PATENT OFFICE.

JAMES L. HAMILTON, OF GRAND JUNCTION, COLORADO, ASSIGNOR OF ONE-FOURTH TO
W. R. HAINES AND ONE-FOURTH TO CHARLES VAN HOOSBEKE, BOTH OF GRAND
JUNCTION, COLORADO.

ORCHARD-HEATING DEVICE.

940,965.

Specification of Letters Patent. Patented Nov. 23, 1909.

Application filed January 2, 1909. Serial No. 470,546.

To all whom it may concern:

Be it known that I, JAMES L. HAMILTON, a citizen of the United States, residing at Grand Junction, county of Mesa, and State of Colorado, have invented certain new and useful Improvements in Orchard-Heating Devices; and I do declare the following to be a full, clear, and exact description of the invention, such as will enable others skilled in the art to which it appertains to make and use the same, reference being had to the accompanying drawings, and to the figures of reference marked thereon, which form a part of this specification.

5 My invention relates to improvements in orchard devices, my object being to provide an article of this character which shall be well adapted for use in raising the temperature sufficiently in the vicinity of orchards, gardens and in all localities containing vegetation, to prevent injury thereto by frost.

20 My improved device comprises a receptacle for liquid fuel, as oil, in which is located an adjustable partition or bulk head, whereby the receptacle may be divided into two compartments having any desired relation to each other as regards volume or capacity. On one side of the partition the liquid fuel is lighted and this compartment forms a 25 combustion chamber; while on the opposite side the liquid fuel constitutes a source of supply for the combustion compartment. While the partition fits quite closely within the receptacle, the oil will pass between its 30 adjacent edges and the walls of the receptacle and maintain the liquid fuel at the same 35 level in both compartments.

40 My improved device is exceedingly advantageous for the purpose stated, from the fact that by simply adjusting the partition separating the two compartments, an increase in heat from each individual device may be obtained, since by the movement of the partition the size of the combustion 45 chamber or compartment is enlarged, exposing an increased surface area of the burning liquid. It is evident that the fuel receptacle may be made of any desired size whereby a sufficient quantity of oil may be placed 50 therein to last an entire season. By the adjustment of the partition a small quantity of liquid fuel may be exposed, or a considerable quantity, as desired, while with other devices intended for use in heating orchards, 55 so far as I am aware, in order to increase the

heating capacity it is necessary to add additional heating devices, since each device is a unit, and its heating capacity cannot be increased. This is believed to be true so far as all devices of this character for the burning of liquid fuel are concerned.

The facility with which my device may be regulated for the purpose of increasing the heat, is exceedingly important, since it often happens that there is a sudden fall of temperature, and under ordinary circumstances, or where other heaters are used, there would not be sufficient time to place additional heaters in the orchards until the damage had resulted; while with my device a single 70 individual can quickly adjust the partition of a great many of these devices, and thus immediately increase the fire or heating capacity of each device. This is also very important for the reason that during the 75 period when devices of this character are needed, it is usually difficult to obtain workmen, and where a considerable number are required, it is often impossible to obtain them. With my device no difficulty of this 80 kind can arise, for the reason heretofore stated.

Having briefly outlined my improved device, I will proceed to describe the same in detail, reference being made to the accompanying drawing in which is illustrated an embodiment thereof.

In this drawing, Figure 1 is a perspective view of my improved orchard heater. Fig. 2 is a vertical longitudinal section of the 90 same, showing the cover and partition or bulk head adjusted for use, the receptacle being provided with liquid fuel. Fig. 3 is a cross section of the device taken on the line 3—3 Fig. 2. Fig. 4 is a perspective view 95 in detail of one form of the partition or bulk head. Fig. 5 is a similar view of another form of said partition.

The same reference characters indicate the same parts in all the views.

Let the numeral 5 designate a receptacle adapted to contain liquid fuel, as oil, which is designated in Fig. 2 by the numeral 6. This receptacle is provided near its top with perforations 7, which preferably extend entirely around the receptacle, that is to say, on all four sides thereof. As shown in the drawing, one extremity of the receptacle has its side and end walls formed somewhat higher than the corresponding walls of the 101

opposite portion. The part having the higher walls may be designated the forward end of the device, or that where the fuel is to be lighted, and which will constitute the combustion chamber. This portion of the device is provided with additional perforations 7 formed in the upper portion 8 of the side and end walls. Located within this receptacle is the partition or bulk head 9, which, if of the form shown in Figs. 2 and 4, is preferably formed hollow, as shown at 10, and composed of fire clay, or other material adapted to resist the action of the heat in the combustion chamber. This partition may be of the construction shown in Fig. 5, in which the body part is composed of a metal plate 12 having side wings 13, an asbestos member 14 being applied thereto to prevent the heat from passing readily from the combustion compartment to the contents of the receptacle on the opposite side of the partition. This asbestos member occupies a position in contact with the metal plate 12 and between the side wings 13. It is evident that many different forms of construction for this partition may be employed. Any suitable form may be used that is adapted to prevent the too rapid travel of the heat from the combustion chamber to the chamber containing the source of fuel supply.

It is evident that it is not desirable that the liquid fuel in the reserve chamber should be unduly heated. It will, however, be kept warm or of sufficient temperature to cause it to flow readily, thus putting it in proper condition for passing around the partition into the combustion chamber with sufficient freedom to maintain the level of the fuel the same in both compartments.

Whichever style of partition is employed, it is made to fit the opposite side walls of the receptacle 5, and is readily slidable therein. The side walls of this receptacle are preferably inclined, whereby the receptacle is widest at the top and diminishes in width toward the bottom. By virtue of this construction, a partition whose opposite edges fit between the two side walls will be sure to maintain an upright position at all times. When formed of fire clay, or other similar material, it is important that the partition or bulk head should be hollow or provided with an air chamber which is well adapted to prevent the passage of heat through the partition. It is evident that in choosing material for this bulk head or partition, those substances possessing a high degree of heat conductivity should be avoided.

My improved device is further provided with a cover 15, which is slidably mounted between the side walls of the receptacle. The upper edges of these walls are turned inwardly, as shown at 16, to form guide ways for this cover, whose forward portion rests

upon the upper extremity of the partition or bulk head 9. The forward extremity of this cover is turned upwardly, as shown at 17, and is provided with perforations 7 lying in the same plane with the corresponding perforations of the upper part 8 of the walls of the receptacle. The forward portion of the cover is also provided just in the rear of the flange 17, with an opening 18, which, when the cover is properly adjusted, registers with the chamber 10 of the hollow bulk head. When the cover is so adjusted, a tool (not shown), of any suitable character may be inserted in the opening 18, whereby it is caused to protrude into the chamber 10, whereby the cover and bulk head or partition may be moved back and forth simultaneously.

From the foregoing description, the use of my improved device will be readily understood. Any desired number of these devices may be located in the orchard or other locality needing protection from frost. The devices may be located at such intervals as desired. Each receptacle 5 should be supplied with a quantity of fuel oil. In the first instance the partition 9 should be adjusted to expose any desired surface area of the oil, according to the amount of fire required. If it is only desired to produce a small quantity of heat, the partition is moved to expose a corresponding surface of the oil, while if a greater fire should be required, the partition is readily adjusted to expose a greater area of the liquid fuel within the combustion chamber, or forward extremity of the receptacle. When this is done the oil within the exposed compartment of the receptacle is lighted, the cover 15 being adjusted so that its forward extremity shall rest upon the top of the bulk head or partition.

The function of the perforations 7 at the left of the partition is to allow the escape of any gas that may be formed, due to the heating of the oil, or liquid fuel, within the compartment at the left of the partition, referring to Figs. 1 and 2. These perforations are therefore considered an element of safety to prevent possible explosion, due to the formation of gas by heat conducted from the combustion chamber. They may be used or not, as desired.

Having thus described my invention, what I claim is:

1. A heating device, for the purpose stated, comprising a receptacle for liquid fuel, a partition or bulk head located therein dividing the receptacle into two compartments, the said partition being adjustably mounted in the receptacle and arranged to permit the flow of fuel from one side of the partition to the other, for the purpose set forth.

2. A device of the class described, compris-

ing a receptacle for liquid fuel, a partition or bulk head adjustable longitudinally therein and arranged to permit the flow of fuel from one side of the partition to the other, 5 and a cover slidably mounted on the receptacle, for the purpose set forth.

3. An orchard heater comprising a liquid fuel receptacle, an adjustable bulk head arranged to permit the flow of fuel from one 10 side of the bulk head to the other, and a cover movably mounted on the receptacle.

4. A heater of the class described, comprising a liquid fuel receptacle, a partition separating the receptacle into two compartments and arranged to permit the flow of fuel from one side of the partition to the other, and a cover adjustably mounted on the receptacle, the latter being provided with 15 perforations below the plane of the cover and above the level of the liquid fuel, substantially as described.

5. A heater of the class described, comprising a receptacle for liquid fuel, a cover adjustably mounted thereon, a partition dividing the receptacle into two compartments, one of which forms a combustion chamber the partition being adjustable and arranged 20 to permit the flow of fuel from one side thereof to the other, the walls of the portion 25 of the receptacle forming the combustion chamber being somewhat higher and provided with perforations above the plane of the cover, substantially as described.

6. An orchard heater, comprising a receptacle for fuel oil, a hollow partition or bulk head mounted in the receptacle and dividing the latter into two compartments the partition being adjustable and arranged to permit the flow of the fuel from one side of the partition to the other, the upper portion of 40 the receptacle above the level of the fuel having a row of perforations, one extremity of the receptacle having its walls higher than the opposite portion, and containing an additional row of perforations, and a cover 45 slidably mounted on the receptacle and occupying a plane between the two rows of perforations, the forward portion of the cover resting upon the partition, substantially as described.

7. The combination of a liquid fuel receptacle and an adjustable partition therein, said partition being arranged to permit the flow of fuel from one side thereof to the other.

8. The combination of a liquid fuel receptacle, an adjustable cover therefor, and a partition adjustable therein, the said partition being arranged to permit the flow of fuel from one side thereof to the other.

In testimony whereof I affix my signature 60 in presence of two witnesses.

JAMES L. HAMILTON.
